UNITED STATES PATENT OFFICE.

MINOTT W. SEWALL, DECEASED, LATE OF NEW YORK, N. Y., BY SUSANN E. SEWALL,
EXECUTRIX, OF NEW YORK, N. Y., ASSIGNOR TO THE BABCOCK & WILCOX COMPANY,
OF BAYONNE, NEW JERSEY, A CORPORATION OF NEW JERSEY.

STEAM-BOILER.

1,140,406.

Specification of Letters Patent. Patented May 25, 1915.

Application filed July 30, 1914. Serial No. 854,155.

To all whom it may concern:

Be it known that MINOTT W. SEWALL, late a citizen of the United States, and a resident of the city, county, and State of New York, did invent certain new and useful Improvements in Steam-Boilers, of which the following is a specification.

This invention relates to steam boilers and more particularly to a system of tubing part 10 of which constitutes a water-protected roof for the furnace of a Stirling boiler.

The invention will be understood by reference to the accompanying drawings in which—

15 Figure 1 is a vertical section, partly in outline of a Stirling boiler; and Fig. 2 a view to illustrate a modification.

In the drawings the numerals 1, 2 and 3 designate the usual transverse steam and water drums of a Stirling boiler, these drums being connected by inclined banks of generating tubes 4, 5 and 6, respectively, with a mud drum 7. These parts are indicated only in outline, the construction being 25 one well-known.

8 indicates the furnace chamber at the rear of which is a bridge wall 9.

Instead of the usual furnace arch, a row 30 of tubes 10 is introduced, which tubes are expanded at their inner ends into mud drum 7 and are inclined upwardly therefrom to a cross box or water chamber 11. The latter is supported in the front wall above the furnace door 12 parallel with and intermediate the levels of the upper and lower 35 boiler drums, and is connected with the front drum 1 by a row of substantially vertical tubes 13. Extending from chamber 11, rearwardly, is a baffle 14 which terminates 40 short of the mud drum 7 so as to provide an opening for the escape of the gases from the furnace chamber into the secondary combustion chamber above the furnace roof. A wall 15 supported on the tubes 13 prevents 45 the escape of gases outwardly around drum 1. Any suitable system of baffling may be employed to direct the gases along or among the generating tubes.

Instead of straight tubes connecting drum 1 and manifold 11, tubes 16, curved at their lower ends and entering manifold 11 at the side thereof alternately with the roof tubes 10, may be used, as shown in Fig. 2.

What is claimed and desired to be secured by Letters Patent of the United States is:—

1. A water tube boiler having upper transverse steam and water drums and a lower mud drum, banks of generating tubes connecting said drums, a transverse water chamber intermediate the levels of the upper and lower drums, a row of tubes connecting the mud drum and said chamber and extending over the boiler furnace, and a row of tubes connecting said chamber with one of the upper drums.

2. A water tube boiler having a plurality of upper transverse steam and water drums and a lower mud drum, banks of generating tubes connecting said drums, a transverse water chamber intermediate the levels of the upper and lower drums, a row of tubes connecting the mud drum with said chamber, and a baffle extending from said chamber rearwardly, said row of tubes and baffle constituting the roof of the combustion chamber.

3. A water tube boiler having a plurality of upper transverse steam and water drums and a lower mud drum, banks of generating tubes connecting said drums, a transverse water chamber intermediate the levels of the upper and lower drums, a row of tubes connecting the mud drum with said chamber, a baffle extending from said chamber rearwardly, said row of tubes and baffle constituting the roof of the combustion chamber, and a row of tubes connecting said chamber and the front steam and water drum.

In testimony whereof I have hereunto signed my hand in the presence of two subscribing witnesses.

SUSANN E. SEWALL,
Executrix of the estate of Minott W. Sewall,
deceased.
